UNITED STATES PATENT OFFICE.

MARK A. BROWN, OF CHATTANOOGA, TENNESSEE.

CAR-COUPING.

1,127,584.

Specification of Letters Patent.

Patented Feb. 9, 1915.

Application filed August 13, 1913. Serial No. 785,430.

To all whom it may concern:

Be it known that I, MARK A. BROWN, a citizen of the United States, residing at Chattanooga, in the county of Hamilton 5 and State of Tennessee, have invented a new and useful Car-Coupling, of which the following is a specification.

The invention relates to improvements in car couplings.

10 The object of the present invention is to improve the construction of car couplings, and to provide a simple, efficient and comparatively inexpensive car coupling designed to meet all the requirements of the 15 Master Car Builders' Association and the Interstate Commerce Commission, and capable of coupling automatically and of being readily uncoupled without going between cars.

20 A further object of the invention is to provide a car coupling having a ball bearing locking knuckle and provided also with an inclined supporting surface receiving the balls of the bearing and adapted to enable 25 the same to overcome the frictional resistance to the opening movement of the knuckle, whereby a positive automatically opening gravity acting knuckle is produced adapted to open completely after the car 30 coupling has been set for automatic coupling and the cars have been separated and the knuckle is free to open.

Another object of the invention is to provide a freely slideable lock set adapted to 35 hold the knuckle locking means out of engagement with the knuckle, and capable of being readily actuated by the knuckle in its closing movement to release the knuckle locking means and permit the same to engage the knuckle.

Furthermore, it is the object of the invention to provide a ball bearing laterally shiftable car coupling and to construct and 45 arrange the operating device of the knuckle locking means so that such device may be employed for laterally adjusting the car coupling from the side of the car to position the car coupling properly for automatic coupling without going between the 50 cars.

A further object of the invention is to provide means for automatically unlocking the knuckle should the draw head become disconnected from the draft rigging.

55 With these and other objects in view, the

invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages 60 of the invention.

In the drawings: Figure 1 is a side elevation of a car coupling, constructed in accordance with this invention, and equipped with an air brake coupling or connector 70 and coupled with an ordinary pivoted knuckle car coupling having a circular air brake coupling or connector. Fig. 2 is a horizontal sectional view of the improved car coupling. Fig. 3 is a longitudinal sectional view of the same. Fig. 4 is a transverse sectional view on the line 4—4 of Fig. 3. Fig. 5 is a transverse sectional view, taken substantially on the line 5—5 of Fig. 2. Fig. 6 is a transverse sectional view on 80 the line 6—6 of Fig. 1. Fig. 7 is a detail sectional view, taken longitudinally of the ball bearing of the pivoted knuckle. Fig. 8 is a detail sectional view on the line 8—8 of Fig. 7. Fig. 9 is a detail perspective 85 view of the lock set. Fig. 10 is a detail perspective view of the knuckle engaging or locking arm. Fig. 11 is a detail view, illustrating the construction of the depending bearing flanges of the car coupling. 90

Like numerals of reference designate corresponding parts in all the figures of the drawings.

In the accompanying drawings in which is illustrated the preferred embodiment of 95 the invention, 1 designates a draw head provided with a draw bar 2 having an oppositely inclined bottom face 3, extending downwardly and inwardly from the side faces of the draw bar to the center thereof 100 and arranged upon a seat formed by a ball bearing plate 4 mounted within a carrier iron 5. The carrier iron 5 which is suitably secured to the timber or framework of the car, is preferably composed of spaced 105 vertical sides and a straight transversely disposed bottom connecting portion 6, as clearly illustrated in Fig. 4 of the drawings. The ball bearing plate, which has a flat horizontal lower face 7, is fitted against 110

the upper face of the bottom 6 of the carrier iron and extends entirely across the same and is provided at the side edges of the said bottom portion 6 with depending flanges 8, which form a bottom recess to receive the bottom portion 6 of the carrier iron, whereby the ball bearing plate 4 is interlocked therewith. The bearing plate is maintained firmly in interlocked relation 10 with the carrier iron by the weight of the car coupling, it being unnecessary to provide fastening devices for securing the bearing plate to the carrier iron. The upper face 9 of the ball bearing plate, which is oppositely inclined to conform to the configuration of the oppositely inclined bottom faces 3 of the draw bar, is provided with ball receiving grooves 10 of substantially cylindrical form and separated at their inner 20 ends by a central wall 11, which forms a stop for antifriction balls 12. The ball receiving grooves 10, which extend from the central wall to the ends of the bearing plate 4, partially embrace the greater portion of 25 the antifriction balls, which project slightly above the inclined upper face 9 to form a rolling ball bearing support for the draw bar. The antifriction balls are retained in the grooves 10 by the oppositely curved 30 walls thereof and also by the carrier iron, the sides of which close the outer ends of the grooves when the parts are assembled. The oppositely inclined series of antifriction balls are adapted to center the car coupling, 35 and they also enable the same to be easily shifted by a transverse knuckle unlocking shaft 13 for arranging the car coupling in proper position for automatic coupling.

No claim is made in the present application to the ball bearing support for the draw bar, as this forms the subject-matter of a copending application, filed Nov. 10, 1913, Serial No. 800,193.

The draw head, which is entirely closed 45 at the top and sides for excluding dust, water, snow and other accumulation, has a knuckle 14 pivoted to it at one side by a knuckle pin 15. The draw head is provided at the bottom with an inclined face 16 disposed transversely and located in rear of 50 the knuckle pin 15 and receiving antifriction balls 17. The antifriction balls, which may be of any desired number, are arranged in a groove or bore 18 of cylindrical form 55 intersected by the bottom face of the knuckle. The groove 18, which is slightly curved, as illustrated in dotted lines in Fig. 2 of the drawings, embraces the major portion of the opposite faces of the antifriction 60 balls, which project slightly below the bottom face of the knuckle and rest upon the inclined face 16 of the bottom of the draw head. The groove 18 extends to the outer side face of the knuckle and the balls are retained in the groove by means of a screw 65

70 plug 19 engaging interior threads 20 at the outer end of the said groove 18. The angle of repose of the knuckle assisted by the ball bearing is sufficient to overcome the coefficient of friction and produce a positive automatic opening of the knuckle. The automatic gravity action is positive in completely opening the knuckle when the knuckle locking means is supported in an elevated position by a lock set 21, and it is 75 unnecessary to provide operating means for kicking the knuckle open in order to insure a full and complete movement of the same. The antifriction balls 17 are also adapted to ride readily up the inclined face 16 of the 80 bottom of the draw head and to enable the pivoted knuckle to close freely.

75 The knuckle 14 is provided with an inwardly and rearwardly extending arm 22, which is approximately L-shaped to enable it to interlock with an interior shoulder 23 of the adjacent side of the draw head when the knuckle is closed. When the knuckle is closed, the arm 22 is engaged by an approximately L-shaped locking arm 24 arranged 85 to swing upwardly and downwardly out of and into engagement with the arm of the knuckle, and consisting of a forwardly or outwardly extending attaching portion, which is provided with an opening 25 to 90 receive the shaft 13. The forwardly or outwardly extending portion of the locking arm is adapted to rest upon the bottom of the draw head when the knuckle is closed, and it presents a flat side face to the arm of the 95 knuckle and it is adapted to swing upwardly and rearwardly to the dotted line position illustrated in Fig. 3 for releasing the knuckle. When the locking arm is manually operated to swing it out of engagement 100 with the knuckle, it is carried upwardly a sufficient distance to permit the lock set 21 to move out of a recess 26 into the path of the locking arm to its supporting position. The outer side face and lower edge of the 105 locking arm are rounded at 27 to permit the knuckle in its closing movement to engage and lift the locking arm sufficiently to pass the engaging portion thereof, which automatically drops into engagement with the 110 arm of the knuckle and locks the latter in its closed position. The lock set when in its supporting position extends into the path of the arm of the knuckle so that the knuckle in 115 opening moves the lock set backwardly from the locking arm, which drops slightly and rests upon the arm of the knuckle, and the latter in its closing movement does not lift the locking arm sufficiently to permit the lock set to move beneath the same and interfere with the complete downward locking movement thereof. The lock set 21 consists 120 substantially of an oblong block rounded at the front edge at 28 and provided at the rear edge with a lug 29 operating in a 125 130

branch or extension 30 of the recess 26 and offset from the inner supporting end of the lock set and adapted to permit the inner supporting end of the lock set to extend beneath the engaging portion of the locking arm before the said lug 29 comes in contact with the same and checks such downward and inward movement of the lock set. The recess 26 inclines downwardly and inwardly, as clearly shown in Fig. 5 of the drawings, and the lock set slides downwardly and inwardly by gravity to its supporting position when the engaging portion of the locking arm is lifted clear of the inner end of the lock set.

The opening 25 is rectangular, and the shaft 13, which is preferably square, extends through the said opening 25 and is supported in bearing openings 31 of spaced flanges 32, formed integral with and depending from the lower face of the bottom of the draw head and extending rearwardly from the front or outer end of the same. The bottom of the draw head is provided with a slot 33 through which the lower portion of the locking arm extends; the draw head is also provided with a depending transversely disposed stop flange 34, located at the front end of the slot 33 and projecting from the inner face of one of the bearing or supporting flanges 32. The opening 25 is located at a point intermediate of the top and bottom of the locking arm, which projects below the transverse operating shaft 13, and the flange 34, which is arranged in advance of the said shaft 13, forms a stop for and is adapted to be engaged by the lower end of the locking arm to limit the upward swing thereof when the said locking arm is lifted by the arm of the knuckle. This prevents the locking arm from being thrown upwardly by the knuckle a sufficient distance to release the lock set and permit the same to move to its supporting position. When, however, it is desired to arrange the parts for automatic uncoupling, the shaft 13 is manually rotated and the openings 31, which are elongated and arranged at an inclination, permit the lower end of the locking arm, which is rounded, to fulcrum against the stop flange 34 and force the shaft 13 upwardly and rearwardly from the lower ends of the openings to elevate the engaging portion of the locking arm to the dotted line position shown in Fig. 3. This permits the locking arm to be moved clear of the inner supporting portion of the lock set. The shaft is provided at opposite sides of the draw head with set collars 35 to prevent the longitudinal movement of the shaft, and the latter is equipped at its ends with suitable crank handles 36 provided at their shanks or attaching portions with sockets 37, which are keyed or otherwise secured to the ends of the shaft.

The handles or operating arms 36 of the shaft 13 are located at the sides of the car and they are adapted to be readily grasped for raising the locking arm and also for moving the draw head laterally to arrange the same in proper position for coupling. The operating shaft is also provided with an arm 38 located beyond the draw head and adapted when the car coupling is used on a freight car to be connected by a safety chain 75 39 with the end sill 40 or other portion of the car, whereby the chain will be tightened and the operating shaft 13 will be partially rotated and the knuckle unlocked should the draw head become disconnected from the 80 draft rigging or other fastening means. This will prevent the draw bar from pulling out and falling upon the track. When, however, the car coupling is mounted on a coach or other car of a passenger train, the 85 arm 38 is connected by a chain with a platform unlocking lever, and it then performs the double function of a safety device and a connection between the shaft and the said lever. This construction will enable the car 90 coupling to be unlocked by the said lever and will also automatically unlock the knuckle should the car coupling become disconnected from its fastening means. The supporting flanges 32 are also adapted to 95 have secured to them by bolts 41 or other suitable fastening devices a bracket 42, which supports the rear portion of one of the members 43 of an air brake coupling or connector, constructed substantially the same 100 as that shown and described in an application filed by me on or about the 6th day of April, 1910, Serial No. 553,726. The supporting bracket 42 is provided at the top with spaced attaching portions 44, which are 105 approximately L-shaped forming horizontal flanges 45, which extend laterally from the attaching portions 44 at the upper end of the bracket. The upper end of the bracket is adapted to straddle the supporting flanges 110 32 and the bolts pierce the attaching portions and the said flanges when the bracket 42 is applied to the improved car coupling. The horizontal flanges 45 enable the bracket to be secured to the shank or draw bar 46 115 of an ordinary car coupling 47 by a U-bolt 48, as clearly shown in Fig. 6 of the drawings. The spaced attaching portions 44 of the supporting bracket are provided at their inner faces with recesses 49 to receive the 120 bottom portion of the shank or draw bar 46, which fits between the attaching flanges 45 to enable the supporting bracket to be firmly and securely fastened to the said draw bar. The supporting bracket consists 125 of approximately vertical upper and lower portions and an inclined intermediate portion, which offsets the lower portion from the transverse vertical plane of the upper portion. By this construction, the support- 130

ing bracket is adapted to be reversed to arrange its upper attaching portion at the outer or inner portion of a car coupling without changing the position of the lower 5 end in which the member 43 of the car coupling or connector is mounted. In Fig. 1 of the drawings at the right hand side, the bracket 42 is shown applied to the improved car coupling and the upper attaching portion of the car coupling is located in rear of the lower supporting portion of the said bracket. At the left hand side of Fig. 1 of the drawings, the supporting bracket is shown applied to the ordinary car coupling 10 15 20 25 30 35 40 45 50 55 60 65 70 75 80 85 90 95 100 105 110 115 120 125 130

The outer portion of the member 43 of the air brake coupling or connector is supported by side chains 50, secured at their upper ends to the shank or draw bar of the car coupling by a U-bolt 51 or other suitable means and extending downwardly and outwardly and having their lower ends linked into openings of lugs 52 formed integral with the said member 43 of the air brake coupling or connector. The chains 50 are adapted to support the members of the air brake coupling or connector in a horizontal position for automatic coupling, and in practice the chains 50 will have sufficient slack to permit a downward play of the air brake coupling or connector of about four inches from their normal horizontal position. This will be sufficient to permit the air brake coupling or connector to yield to the various movements of a train in motion and will also enable the chains to operate as stay chains and cause a positive separation of the members of the air brake coupling or connector should a car leave the rails as there will be a drop of from six to eight inches at least under such conditions.

No claim is made in the present application to the extension bracket for supporting the air brake coupling or connector, as this forms the subject-matter of a copending application, filed Nov. 10, 1913, Serial No. 800,192.

55 What is claimed is:—

1. A car coupling including a draw head having an inclined face, a knuckle pivoted to the draw head and provided with a bore intersected by the lower face of the knuckle, 60 an antifriction ball mounted in the bore and projecting beyond the lower face of the knuckle, and arranged to run on the inclined face of the draw head, and the walls inclined face of the draw head, and the walls 65 of the bore embracing the major portion of

the ball, whereby the same is confined in the bore and is carried by the knuckle.

2. A car coupling including a draw head having an inclined face, a knuckle pivoted to the draw head and provided with an approximately cylindrical bore having an outer threaded portion and intersected by the lower face of the knuckle, an antifriction ball mounted in the said bore and carried by the knuckle, said ball projecting beyond the lower face of the knuckle, and arranged to run on the inclined face of the draw head, and a screw plug engaging the threads of the bore and confining the ball within the same. 70 75 80 85 90 95 100 105 110 115 120 125 130

3. The combination with a draw head having a draw bar, a pivoted knuckle mounted on the draw head, and a locking device for the knuckle including a transverse shaft, of means for mounting the draw bar and for normally centering the draw head and for also permitting the draw head to be moved laterally in either direction to arrange the knuckle opposite the knuckle of a companion car coupling, said shaft projecting beyond the draw head and forming a handle for moving the same laterally. 85 90 95 100 105 110 115 120 125 130

4. A car coupling including a draw head, a pivoted locking device arranged to swing upwardly and downwardly and adapted to lock the knuckle in its closed position, and a gravity acting lock set consisting of a block slidable bodily on the draw head in a direction laterally thereof and abutting against the side face of the locking block when the knuckle is closed, said block being movable inwardly automatically beneath the locking device and adapted to support the same in an elevated position when the said locking device is raised. 95 100 105 110 115 120 125 130

5. A car coupling including a draw head, a pivoted knuckle, a pivotally mounted locking arm arranged to swing upwardly and downwardly into and out of engagement with the knuckle, and a slidably mounted lock set movable laterally of the draw head into and out of the path of the locking arm and provided with a projecting lug arranged to engage the locking arm to limit the movement of the lock set. 105 110 115 120 125 130

6. A car coupling including a draw head having a transverse recess arranged at an inclination, a pivoted knuckle, a locking arm arranged to swing upwardly and downwardly into and out of engagement with the knuckle, and a lock set having an inclined bottom face and slidable in the said recess in a direction laterally of the draw head and provided at a point intermediate of its ends with a lug arranged to limit the sliding movement of the lock set. 115 120 125 130

7. A car coupling including a draw head having an enlarged bearing opening, a pivoted knuckle, a shaft mounted in the bearing opening and provided with an arm arranged to engage the knuckle and adapted 130

to be lifted by the same in the closing movement thereof, an automatic lock set movable into and out of the path of the locking arm, means for manually operating the said shaft, 5 and means located in the path of the arm for automatically sliding the shaft upwardly in the enlarged bearing opening to carry the locking arm beyond the lock set.

8. A car coupling including a draw head, 10 a pivoted knuckle, a locking arm arranged to engage the knuckle and adapted to be lifted by the same in the closing movement thereof, a lock set movable into and out of the path of the locking arm, means for limiting 15 the movement of the locking arm when actuated by the knuckle to prevent the locking arm from moving beyond the lock set, whereby the latter is held out of the path of the locking arm, and manually operable 20 means connected with the locking arm and arranged to carry the same beyond the lock set to permit the latter to move to its supporting position.

9. A car coupling including a draw head 25 provided with an inclined bearing opening, a pivoted knuckle, a shaft mounted in the said bearing opening, a locking arm mounted on the shaft and arranged to swing upwardly and downwardly into and out of 30 engagement with the knuckle and adapted to be lifted by the latter in the closing movement thereof, said locking arm having a projecting portion, an automatic lock set movable into and out of the path of the 35 locking arm, a stop located in the path of the said projecting portion of the locking arm for limiting the swing of the same when actuated by the knuckle, and manually operable means for operating the 40 shaft, whereby the projecting portion of the locking arm is caused to fulcrum against the said stop to carry the locking arm beyond the lock set.

10. A car coupling including a draw head 45 provided at the bottom with a depending bearing having an inclined opening, a pivoted knuckle, a shaft mounted in the said inclined bearing opening, a locking arm arranged to engage the knuckle and extending 50 through the bottom of the draw head and mounted on the said shaft and projecting below the same, said locking arm being

adapted to be lifted by the knuckle in the closing movement thereof, an automatic lock set, and a stop arranged in the path of the 55 lower projecting portion and adapted to limit the movement of the locking arm when the same is actuated by the knuckle and forming a fulcrum for the projecting portion of the locking arm and permitting the 60 same to be swung beyond the lock set.

11. A car coupling including a draw head provided at the bottom with spaced depending flanges having enlarged bearing openings, a shaft mounted in the said openings, 65 a knuckle pivoted to the car coupling, a locking arm mounted on the said shaft and having a projecting portion, said locking arm being arranged to engage the knuckle and adapted to be lifted by the same in the 70 closing movement thereof, a stop flange located in advance of the bearing openings and arranged in the path of the projecting portion of the locking arm to limit the opening movement thereof when actuated by 75 the knuckle, and means for operating the shaft to cause the projecting portion of the locking arm to fulcrum on the stop flange, whereby the locking arm is swung beyond the lock set. 80

12. A car coupling including a draw head having a laterally inclined face, a pivoted knuckle, a pivotally mounted locking device arranged to swing upwardly and downwardly and adapted to engage and release 85 the knuckle, and a lock set consisting of a block having an inclined lower face and arranged upon the inclined face of the draw head, said block being slidable bodily in a direction laterally of the draw head and 90 abutting against the side face of the locking device when the knuckle is closed, said block being also movable inwardly automatically beneath the locking device and adapted to support the locking arm in an elevated position when the said locking device is raised. 95

In testimony, that I claim the foregoing as my own, I have hereto affixed my signature in the presence of two witnesses.

MARK A. BROWN.
